UNITED STATES PATENT OFFICE.

HARRY BENTON YOUNG, OF MOUNT HOLLY, NEW JERSEY.

CALENDAR.

No. 926,799.

Specification of Letters Patent.

Patented July 6, 1909.

Application filed April 11, 1908. Serial No. 426,464.

To all whom it may concern:

Be it known that I, HARRY BENTON YOUNG, citizen of the United States, residing at 212 Clifton avenue, Mount Holly, in the 5 county of Burlington and State of New Jersey, have invented certain new and useful Improvements in Calendars, of which the following is a specification.

My invention relates to calendars, more 10 particularly to that type of calendar which is known as perpetual, and it consists in the combinations, constructions and arrangements herein described and claimed.

The object of my invention is to provide a 15 device which is compact and convenient and by which any day of any year (the number of years available being limited only by the size of the card) can be determined with ease and accuracy, and without the necessity of mental calculations, or the liability of making error through the incorrect tracing of intersecting columns. I accomplish this object by arranging two charts or diagrams so that in certain relative positions sections on one 20 chart are adapted to register with sections on the other chart, whereupon the desired information can be immediately and directly read off from the proper chart which contains it.

30 My invention is illustrated in the accompanying drawings in which:—

Figure 1 shows a plan of the larger chart, and Fig. 2 shows a plan of the smaller chart.

Referring now to Fig. 1, I have shown 35 therein a disk of septagonal shape and denoted in general by A. From the seven corners of the disk radial lines, a, extend inwardly toward the center, b, terminating about half way between the center, b, and 40 the corners, c, of the disk. The seven divisions thus provided contain certain numerals, the latter being arranged according to the following plan: The two outer rows of each of the seven divisions contain numerals, 45 representing years of the nineteenth century *i. e.* years from 1800 to 1899. The next three rows contain numerals representing years of the twentieth century *i. e.* years from 1900 to 2000. Between the fifth row of numerals and the center, b, is the name of a day 50 in the week, the names in adjacent sections following each other in regular order, reading from left to right or "clockwise".

Fig. 2 shows another disk B which is also 55 preferably of septagonal shape. The radial lines a' from the corners also divide this disk

into seven sections each containing numerals and abbreviations of the names of the months. The outer row of each section contains numerals representing days of the 60 month, while between these rows and the center b' are abbreviations and names of the various months together with a numeral designating the number of days in the particular month with which it is associated. 65

I construct my improved calendar by placing the disk B upon the disk A and passing a pivot pin through their centers. The smaller disk B may then be rotated about its center until its radial lines a' register with the lines a of the larger disk or until its sections register with the sections of the larger disk.

In order to show the use to which the calendar may be put I will take a concrete case. 75 Suppose it be desired to find out what day of the week the 24th of October 1857 fell upon. The year 1857 is first located and then the smaller disk B is turned until the section marked Oct. registers with that containing the year 1857. Now if the 24th day of the month be found, the day of the week on the large disk, immediately above the numeral 24 on the small disk will be the day wanted. In this case it is Saturday. It 80 will be observed that certain years are enclosed in circles. These are the leap years. The months of January and February have two sections each on the small disk. When a leap year is taken and in connection therewith either one of the months of January or February then only that month which is starred should be used: Thus for finding the day of the week upon which Feb. 14, 1888 fell that section of the smaller disk containing * Feb. should be used. Obviously when a certain day is given the date corresponding to it can be found by my calendar, this being merely a reversal of the process already explained. Other years may be added to the calendar by enlarging the larger disk. The two disks may be of circular or other shape without departing from the spirit and scope of the invention. 95

Having thus described my invention, what 100 I claim as new and desire to secure by Letters Patent of the United States, is:

In a calendar, a large and a small disk pivotally connected together and each being divided into exactly seven exposed sections 110 by radial lines, the sections on one disk being adapted to register with those on the

other, numerals representing years, and the name of a day of the week in each section of the larger disk, of said numerals those representing leap years having distinctive marks, 5 and names of months in each section of the smaller disk—each of the months except January and February being represented on the smaller disk in some one of seven sections and January and February each being 10 represented in two of said sections, the Janu-

ary and February each having distinctive marks in the sections required to be used with the leap year numerals.

In testimony whereof I affix my signature in presence of two witnesses.

HARRY BENTON YOUNG.
